UNITED STATES PATENT OFFICE

109,879

DESIGN FOR A COMBINATION PENCIL, CORKSCREW, AND BOTTLE OPENER

Walter Ruby, Long Beach, Long Island, N. Y.

Application August 3, 1937, Serial No. 70,865

Term of patent 14 years

To all whom it may concern:

Be it known that I, Walter Ruby, a citizen of the United States and resident of Long Beach, Long Island, in the county of Nassau and State of New York, have invented a new, original, and ornamental Design for a Combination Pencil, Corkscrew and Bottle Opener, of which the following is a specification, reference being had to the accompanying drawing, forming a part thereof, in which

Fig. 1 is a side elevation of a combination pencil, corkscrew, and bottle opener with the corkscrew element inserted in the top of the pencil

as when the article will be used for writing, showing my new design;

Fig. 2 is another elevational view taken at right angles to the disclosure in Fig. 1;

Fig. 3 is an exploded view of the article shown in Figs. 1 and 2, the parts being joined by a bracket.

I claim:

The ornamental design for a combination pencil, corkscrew and bottle opener, substantially as shown and described.

WALTER RUBY.
